UNITED STATES PATENT OFFICE.

CHARLES W. EISELE, OF FLINT, MICHIGAN.

LAMP DIMMER.

Application filed October 14, 1921. Serial No. 507,711.

My invention relates to lamp dimmers or anti-glare devices for vehicle head lights. While the invention is designed for embodiment in lights for automobiles, motor boats, tractors, locomotives and railway cars, it may be adapted to lamps for other purposes. The present invention is a further development and amplification of the invention disclosed in my Patent No. 1,335,727, issued April 6, 1920, and particularly an amplification and continuation of the disclosure of Letters Patent No. 1,426,162, dated August 15, 1922. This invention contemplates a head light of the usual type, comprising an incandescent bulb located within a parabolic or concave reflector, in combination with a solenoid having a hollow or tubular shield or sleeve, adapted to be intermittently projected to a position within the reflector to intercept the rays of light which would otherwise be reflected as is shown in my co-pending application aforementioned. The present invention embodies new and novel means of locking or temporarily restraining the reciprocatory hollow solenoid core in its assumed position at the opposite limits of its stroke.

The object of the invention is to simplify the structure as well as the means and mode of operation of lamp dimming or antiglare devices, whereby they will not only be cheapened in construction, but will be more complete in use, uniform in action, positive in operation, easily controlled, and unlikely to get out of order.

A further object of the invention is to improve the control means for the reciprocatory action and to provide automatic locking means therefor for temporarily restraining the movable element, at either limit of its stroke.

A further object of the invention is to eliminate the use of springs as in my prior constructions before mentioned.

With the above primary and other incidental objects in view as will more fully appear in the specification, the invention consists of the feature of construction, the parts and combinations thereof and the mode of operation or their equivalents as hereinafter described and set forth in the claims.

Referring to the drawings, Fig. 1 is a front or face view of a vehicle lamp to which the present invention has been applied. Fig. 2 is a sectional view of the lamp

showing the interceptor or sleeve in its advanced position, the relative position of the solenoid or electromagnetic coil by which the interceptor is controlled. Fig. 3 is an enlarged detail sectional view of the interceptor or tubular sleeve and control means therefor. Fig. 4 is a transverse sectional view on line 4-4 of Fig. 3.

Like parts are indicated by similar characters of reference throughout the several views.

Referring to the preferred form of embodiment of the invention shown in the drawings, 1 is a lamp housing having the usual transparent glass 2. The transparent glass 2 is carried in frame 3, which forms a removable closure for the housing 1. Within the housing 1 is located a reflector 4 of the customary concave form, having positioned therein an incandescent electric lamp bulb or other illuminating element 5. The lamp bulb 5 is preferably though not necessarily fixedly mounted in relation with the reflector 4.

Under normal conditions of use the rays of light emanating from the bulb or illuminating device 5 are reflected from the inner face of the concave reflector 4. The reflector 4 is so proportioned that the rays of light will be condensed in the field of illumination and will be projected in substantially parallel rays as is usual in lamps of this character. However, the particular form of the reflector 4 and its light reflecting function, per se, form no part of the present invention.

Without the reflector 4 the illuminating element 5 affords but a limited degree of illumination. Therefore by intercepting the rays of light emanating from the lamp and permitting only a limited portion of the light rays to reach the reflector 4, the brilliancy or intensity of illumination may be varied.

In the present instance as also in my preceding construction referred to, this interception of the light rays and consequent reduction of brilliancy is effected by the reciprocation of a tubular shield or interceptor which in its forward position encloses the lamp bulb or illuminator 5, preventing the rays of light therefrom from reaching the reflector 4, while in its retracted position it exposes the lamp bulb allowing it to function normally in relation with the reflector. Whereas in my prior constructions, this

interceptor or tubular shield has been spring actuated in one direction, and electrically operated in the opposite direction against the tension of such spring, in the present construction, the spring is entirely omitted, and the tubular interceptor is actuated in alternate directions by an electromagnetic influence.

Mounted intermediate the housing 1 and reflector 4, and in axial alignment therewith is a solenoid, having two windings 7 and 8. This solenoid is supported at its rear end upon a spider 9, or collar having radially inclined ears 10 for attachment to the housing 1. At its forward end the solenoid is supported by an extension 11 of the spool upon which the coil is wound, which extension 11 engages in an opening at the center or apex of the reflector 4. The interior of the solenoid core is of comparatively large diameter. Extending axially therethru is a stem 12 for the lamp bulb 5. This stem for convenience and economy of manufacture has been shown as a length of tubing, peripherally flanged at its rearward end for engagement with the supporting collar or spider 9. At its forward end it carries the usual lamp socket 13 for the engagement of the bulb 5. Mounted for reciprocatory movement within the double wound solenoid is the tubular or hollow core 14, to the forward end of which is attached a tubular extension 15 of aluminum, fibre or other nonmagnetic material, which comprises the shield or interceptor, surrounding the lamp bulb 5, when the core is actuated forwardly. The solenoid core 14 and shield or interceptor 15 are fixedly connected one to the other and moved in unison, under the influence of the solenoid windings 7 and 8. The arrangement is such that when the winding 7 is connected in circuit, the tendency of the tubular solenoid 14 to assume a balanced or symmetrical relation with the windings 7, thrusts the tubular shield or interceptor 15 forwardly to a position enclosing the light bulb as shown in Fig. 2 and by dotted lines in Fig. 3. Likewise upon closing the circuit thru the winding 8, the like tendency of the hollow core 14 to assume symmetrical relation with the coil 8 retracts the interceptor 15 thereby exposing the bulb. Inasmuch as it would be a matter of inconvenience and also wasteful of electrical energy to maintain a constant circulation of current thru one or the other of the windings 7 and 8 to hold the core 14 in its adjusted position, means is provided for temporarily locking the core at either limit of its stroke and hence maintaining the shield or interceptor 15 in either retracted or operative position. To this end the core 14 is provided with a head or internal flange 16. Formed in the head 16

are a plurality of radially disposed bores 65 17, in each of which is located a spring 18, yieldingly mounted within such bore and projecting somewhat beyond the inner ends thereof. The central stem or support 12 for the lamp is provided at a 70 medial point with a peripheral bead 19, over which the detent balls 18 of the solenoid core ride upon its rearward movement. This peripheral head or convex enlargement of the supporting stem 12 is so positioned that the detent balls 18 will engage immediately 75 behind such enlargement when the core 14 is retracted. The spring tension of the balls 18 serve to retain the core in its retracted position, preventing its displacement by the jar and vibration of the vehicle. However, the tension of these retaining balls is such 80 that the influence of the winding 7 is sufficient to overcome the resistance of detent balls 18 causing them to ride over the peripheral bead or obstruction 19, as the core is drawn forwardly. Adjustably mounted upon the forward end of the lamp supporting stem 12 is a tapered collar 20 having 85 therein a peripheral groove 21, within which the detent balls 18 engage at the forward limit of their movement. The collar 20 may be fixedly mounted upon the stem 12, but is preferably screw threaded thereon to enable its adjustment for varying the extent 90 of movement of the core 14. As the core 14 approaches the forward limit of its movement under the influence of the winding 7, the retaining balls 18 will ride up the inclined surface of the collar 20, against the tension of their springs and seat within the peripheral groove 21, thereby temporarily locking the core in its advanced position. The collar 20 is provided with a peripheral 95 flange 22, which limits the forward movement of the core under the influence of the winding. Adjacent to this stop flange 22 there is positioned a collar 23 of fibre, rubber or other material to receive the impact of the core and cushion its arrest. A similar gasket or collar 24 is provided adjacent to the supporting collar or spider 9 to cushion the retrograde impingement of the core.

The solenoid windings 7 and 8 may be controlled by separate push buttons or switches to momentarily close the circuit therethrough to actuate the core in opposite directions. To prevent both windings 7 and 8 being simultaneously interconnected with the source of electrical energy, there has been shown a preferred form of control switch comprising a suitable housing 25, within which is located a pivoted switch bar 26, carrying two plunger stems 27, each surrounded by a spring 28. The springs 28 act upon the pivoted bar 26 simultaneously and hence one against the other to maintain

the bar in its balanced position. The pivoted switch bar 26 is connected through battery or other source of electrical energy with both windings 7 and 8. Adjacent to each end of the switch bar 26 are contacts 29 and 30 connected respectively to the windings 7 and 8. By pressing one of the plunger stems 27 to oscillate the switch bar 26 into engagement with one of such contacts, the spring surrounding the other plunger stem is placed under compression and serves to return the switch bar to break the connection upon the release of pressure. By such construction it is impossible to connect both windings at the same time. The connection is automatically broken upon the release of the pressure of the operator's finger.

In order that the driver may observe the side of the road toward which he must turn in passing an approaching vehicle and to safeguard against dangers and obstructions in the roadway when the lamps are dimmed by the advance of the shield or interceptor 15, such shields or interceptors are provided with small openings 31, so positioned as to cast a restricted beam of light upon the interior of the reflector 4. To maintain the shield in position the solenoid core 14 is splined within the bore or passage of the solenoid core to prevent relative rotation thereof. In order that the friction may be reduced to minimum, the spline or key comprises the spring pressed ball 33 similar to the balls 18 in a bore 34 quite similar to the bores 17. The ball 33 engages in a longitudinally disposed groove or key way 35 in the shell or spool of the coil. The ball 34 is pressed outwardly into such key way or spline and while permitting free longitudinal movement of the solenoid core, it effectually prevents rotation thereof.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features it is to be understood that the invention is not limited to the specific details shown, but that the means and construction herein disclosed comprises the preferred form of several modes of putting the invention into effect, and the invention is therefore claimed in any of its forms or modifications within the legitimate and valid scope of the appended claims.

Having thus described my invention, I claim:

1. The combination with a reflector and a lamp co-acting with the reflector, of a solenoid having a hollow core which in one position of adjustment surrounds the lamp and intercepts the rays thereof, which would otherwise reach the reflector and in its opposite position exposes said lamp, and detent means for the core tending to restrain it at the opposite limits of its range of movement. 75

2. The combination with a reflector and a lamp coacting with the reflector, an electromagnet axially mounted in relation with the reflector, a reciprocatory tubular shield controlled by the electromagnet intercepting the light rays in one position of adjustment, and detent means tending to restrain the shield at the opposite limits of its movement. 80

3. The combination of a lamp and a shield relatively movable in relation with the lamp, a solenoid to the core of which said shield is connected for unison movement, said solenoid including two windings to be alternately energized to move said core, first in one direction and then in the other, and spring means tensioned by the movement of the core for yieldingly restraining the movable shield at the opposite limits of its range of movement. 85

4. In combination, a reflector, a lamp co-acting therewith, a shield shiftable upon the axis of the reflector into and out of position to intercept light rays directed toward the reflector, a solenoid having two coils in tandem, and a core common to both coils to which the shield is connected, and means for alternately energizing the solenoid coils and yielding spring means tensioned by the movement of the solenoid core, the reaction of which yieldingly restrains the shield at the opposite limits of its movement. 95

5. The combination with a reflector of a lamp, and an interceptor for light rays directed toward the reflector, the interceptor being relatively movable, in relation with the lamp, of a solenoid having coils in tandem controlling the movable interceptor, which is shifted to operative position by the influence of one coil and retracted by the influence of the other coil, the movable interceptor being fixedly attached to the core of the solenoid for reciprocatory movement in unison therewith, and spring detent means for yieldingly restraining the core at the opposite limit of its movement. 110

6. The combination with a lamp and an interceptor for rays of light therefrom, which interceptor is movable in relation with the lamp, of a solenoid having coils in tandem, controlling the movable interceptor which is shifted to operative position by the influence of one coil and retracted by the influence of the other coil, and spring detent 125

means for the movable interceptor tending to restrain it in its operative and inoperative positions.

7. In a construction of the character described, the combination with an illuminating element and a shield movable relative thereto, of actuating means therefor including a solenoid having tandem windings, a core common to both windings, and detent means for locking the core at the opposite limits of its range of movements.

8. In a construction of the character described, the combination with an illuminating element and a shield movable relative thereto, of actuating means therefor including a solenoid having tandem windings, a core common to both windings, a yielding plunger carried by the core, a member aligned with the direction of travel of the core having deflections in the surface thereof with which the plunger engages as the core approaches the limit of its movement to temporarily restrain the core in its operated position.

9. In a construction of the character described, the combination with an illuminating element and a shield movable relative thereto of actuating means therefor including a solenoid, a core therefor, having a ball yieldingly mounted therein, and stop means yieldingly engaged by the ball as the core approaches the limit of its movement in either direction to restrain the core in its adjusted position.

10. In a construction of the character described, the combination with an illuminating element and a shield movable relative thereto, of an actuating means therefor including a solenoid, a core therefor, the sleeve of the solenoid being provided with an internal longitudinally disposed spline, and a ball seated in the core and engaging in said spline to prevent relative rotation of the core and the coil of the solenoid.

In testimony whereof, I have hereunto set my hand this 4th day of October A. D. 1921.

CHARLES W. EISELE.
